CLAIM

The ornamental design for a planter as shown and described.

DESCRIPTION

FIG. 1 is a front perspective view of a planter showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The uneven-length broken lines immediately adjacent to the shaded areas represent the bounds of the claimed design and form no part thereof. The remaining even-length broken lines represent portions of the planter that form no part of the claimed design.
